WELDED RAILWAY CAR TRUCK FRAME

Edward J. Charlton, Coatesville, and Lewis W. Edwards, Lancaster, Pa., assignors to Lukens Steel Company, Coatesville, Pa., a corporation of Pennsylvania

Application July 20, 1948, Serial No. 39,658

23 Claims. (Cl. 105—208)

1

This invention pertains to railway rolling stock and more particularly to an improved lightweight welded passenger car truck frame assembly.

For many years, the frame of a railway truck has been made from a steel casting because of the necessity for extreme strength and rigidity. With the recent development of higher railway speeds and lighter weight rolling stock, the desirability of decreasing weight in the railway truck without any loss in rigidity and strength has become of considerable importance. While we are aware that others have appreciated the possibility of decreasing weight in a railway truck, other designs for this purpose have not been felt sufficiently safe or economical to be generally adopted in place of the cast structure. A notable weakness of both the cast structures and in previous semi-welded construction has been the concentration of stress at the junctions of the transoms with the side frames. In the cast frame, excessively heavy webs have been provided at these points to insure rigidity. The present invention is particularly directed to an improved welded frame which has ample strength at the termini of the transoms. Other noteworthy features of the invention include specifically the provision of a rigid box section end transom joining the extremities of the frame, internal bulkheads strategically located in the side frame members, and the elimination of many expensive machining operations, etc.

A primary object therefore, of the invention is to provide a lightweight yet strong and rigid all-welded railway truck frame.

A further object of the invention is to provide a lightweight railway truck frame comprising a unitary weldment fabricated of steel plate that is interchangeable with the generally standard truck frame now in use.

A further object of the invention is to provide a lightweight welded railway truck frame which may be fabricated substantially from standard rolled sheet metal sections and/or steel plate.

A further object of the invention is to provide in railway truck frame construction suitable stiffeners and bulkheads at the junctions of the transoms with the side frame.

A further object of the invention is to provide an improved transom construction for a railway truck frame.

Further objects will be apparent from the specification and drawings in which:

Fig. 1 is a plan of a passenger car railway

2

truck frame constructed in accordance with the invention;

Fig. 1a is an enlarged detail in plan of one of the transom junctions with the side rail partly broken away to show the bulkhead construction;

Fig. 2 is a side elevation of the structure of Fig. 1 partly broken away;

Fig. 3 is an end elevation of the structure of Fig. 2;

10 Fig. 4 is a longitudinal section taken on the line 4—4 of Fig. 1;

Fig. 5 is a transverse section taken on the line 5—5 of Fig. 1;

Fig. 6 is an enlarged sectional detail as seen at 6—6 of Fig. 1;

15 Fig. 7 is an enlarged sectional detail as seen at 7—7 of Fig. 1;

Fig. 8 is a sectional detail as seen at 8—8 of Fig. 6;

20 Fig. 9 is an enlarged perspective detail showing the structure of Fig. 1a; and

Fig. 10 is an enlarged perspective detail of the joint between the side member on the box cross member.

25 The invention comprises essentially the provision in a railway truck frame of a welded box transom, fabricated from a pair of channel members, which is anchored at each end to a welded box side rail through a specially designed transition structure which constitutes an important feature of the truck frame construction in that it provides an opening for the usual truck swing hanger or link and at the same time provides a high degree of rigidity and strength at the junction between the transom and side rail where

30 it is needed. The transom is underslung with respect to the side frames and has a sloping U-shaped web extending entirely through the transom and welded thereto, which forms three sides 35 of the swing link slot. Suitable bulkheads are positioned inside the rails at points of maximum stress, to provide ample rigidity and strength without substantial increase of weight. The interlocking construction of the flanges and webs

40 is such that all necessity for full strength butt-welds through the entire cross-section is eliminated. The ability to provide a suitably strong welded construction of steel plate in a passenger car truck frame enables a reduction of approxi-

45 mately 30% in weight over the previously used cast construction.

45 Referring now more particularly to the drawings, the passenger car truck frame shown in Fig. 1 comprises a pair of side rails 15 and 16 which

50 are centrally connected by means of a pair of

center transoms proper 17 and 18 through specially designed transition structures generally designated 42. Cross members 19 and 20 connect the rails 15 and 16 at their extremities as shown in detail in Fig. 10. The frame is provided with the necessary pedestals 25, 25 and the conventional accessories such as spring pads 21, 21, bolster anchor brackets 22, 22, bell crank brackets 23, 23, brake hanger box brackets 24, 24, all welded to the rails or transoms as the case may be.

Referring now to Figs. 1 and 2, it will be noted that in the illustrated embodiment of the invention, the side rails 15 and 16 are substantially flat on top and of uniform depth between the pedestals 25. This construction enables the bottom plate 26 of each side frame to be carried from the inner leg 25a of one pedestal to the bottom of the other pedestal leg as shown in Fig. 2, thus providing a unitary member across the bottom of each side rail. If desired, plate 26 may be slotted at 26a between the bottom of the rails and the tip of the pedestal 25a. Fig. 9 further illustrates the manner in which plate 26 projects transversely to extend as at 26b downwardly and under the ends of transoms 17 and 18. Figs. 6 and 7 show the spring pads 21 welded to the bottom plate 26.

In plan, the side rails 15 and 16 are thinner between the transoms 17 and 18 than between the transoms and cross-members 19 and 20, but it will be noted that the sides 27 and 28 of each rail are substantially parallel and formed from angle members butt-welded longitudinally along the top of the rail and welded to plate 26 along the bottom, as shown in Fig. 9. For the purpose of clarity, the detailed construction of only one side rail and transom junction will be described since it will be understood that the other side rail and transom structures are identical. The same applies to the cross-members 19 and 20.

As shown in Figs. 1, 2, 6, 7 and 9, each center transom is fabricated from two facing channel members 29 and 30, the flanges of which are butt-welded at 49 to form an enclosed box section giving extreme strength and rigidity to this member. The welded channels are beveled at the bottom of each end and welded to the top surface of a sloping extension 26b on plate 26. The downward slope of extension 26b which forms the bottom of the transition structure, in effect truncates the general pyramid-shape of the transition structure 42 so that the top and two sides thereof converge from the base inwardly to the apex portion 41 while the bottom is more nearly parallel to the top. This feature also lowers the top of the underslung transoms well below the centerline of the side rails and even below the bottom of the side rails (Figs. 6-9) and further permits of variation 60 in the location of the transoms vertically with respect to the side rails.

The apex portion 41 of the transition structure 42 is hollow and generally U-shaped in the horizontal direction, and extends vertically upward from the bottom of the transom and slopes outwardly to provide offset weld lines to the transom base at 41a and the transom top at 41b.

It will be noted in Fig. 1a that side 42a of structure 42 is longer than side 42b to compensate 70 for the thinned central section of the side rails. The top 42c of structure 42 slopes downwardly and is provided with a concave arcuate notch 42d at its inner end. The top of the apex portion 41 has a pair of ears 41c, 41c which are 75

welded to and surrounded by a U-shaped collar 43 to form a trunnion for the swing link (not shown). A pair of drilled tabs 44, 44 on collar 43 accommodate a retainer (not shown) for the swing link pin (not shown) which rides in bushings 45, 45. A wear plate 46 for the bolster (not shown) is welded at the inside of each transom in a vertical line with the swing link trunnion. The upper portion of wear plate 46 is of channel section, the flanges of the portion being welded directly to channel 41, the top being welded to the bottom of collar 43, whereas the lower extremity of the wear plate extends downwardly over the side of channel 30 without any flanges and is likewise welded thereto.

A stiffening bulkhead 47 in structure 42 is illustrated in Figs. 1a and 7. This bulkhead extends from the bend line between extension 26b and plate 26 to the top 42c of bracket 42, and slopes inwardly.

Referring now to Figs. 3 and 9, it will be noted that the sides 42a and 42b of structure 42 slope inwardly towards the top and therefore present a biased stress line along the sides of rail 15. A pair of bulkheads 48, 48' are welded inside rail 15 in registry with the welds of sides 42a and 42b. This construction provides ample reinforcement at the area of concentrated stress. Additional strengthening for the side rails is provided by means of transverse sleeves 49, 49 welded in place between the transition structures 42 at each rail.

Two additional bulkheads 50, 50 are provided in each rail between the bend line for the inner pedestal legs 25a, 25a and the outer termini of spring pads 21, 21. Additional rigidity for the bolster anchor brackets 22, 22 is thus achieved since the supporting webs 22a, 22a for the brackets are welded to the rails 15 and 16 in line with one of the bulkheads 50 in each rail, as shown in Fig. 1. It will be apparent that the bulkheads 48, 48' and 50 provide both vertical and lateral strengthening for the side rails at points of maximum stress since they are located at the transition structures, the pedestal juncture, the bolster anchor bracket weld line, and over the spring pads. Sleeves 49 perform a similar stiffening function at the center section of each side rail.

Attention is also directed to the construction of the truck frame at the extremities of the side rails. In this area, rigidity is achieved by means of sleeves 51, 51 welded to the sides of the rails and in addition, there is provided a pair of transverse cross members 19 and 20 connecting opposite ends of the frame. By way of example, the details at one end of member 19 will be described, but the opposite end of member 19 as well as both ends of member 20 are fabricated in the same way. Therefore, the numerals in the drawings designate identical or similarly related parts. Referring to Figs. 1, 2, 4 and 10, the cross member 19 comprises a channel 19a which extends entirely through the ends of the rails 15 and 16. The webs of each channel 19a face towards the center of the frame and are welded to plates 19b, thus forming a completely enclosed box section for a substantial portion of each member 19. Plates 19b also extend entirely through rails 15 and 16 and are additionally reinforced by a pair of triangular gusset plates 52, 52 which are butt welded to the inside of rail members 21, 21 and plates 19b, 19b.

The sleeves 51 and 49 serve a dual purpose since they not only reinforce the rails 15 and

16 but also provide a convenient means for welding the bulkheads after the plates 27 and 28 have been welded to each other. The inner rail plate 27 is cut to substantially the same outside diameter as the sleeves. These holes are then used by the welder as access holes for welding the bulkheads. Thereupon the sleeves are dropped through the apertures in the inner rail plates and welded to the outer rail plate 28 around the inside diameter of the sleeves and then welded to the inner rail plate 27 around the edge of the aperture and the end of the sleeves. In this way, all the bulkheads 48, 48' and 50 can be welded onto the inner faces of both plates 27 and 28.

It will be apparent that the entire construction of the frame is designed to secure a maximum strength and rigidity at the points of stress concentration through the expedient of providing ample stiffening members at these points. The idea of utilizing bulkheads and plate members instead of increasing the thickness of the frame itself is new in railway track frame construction and effects a great saving in weight. It will be noted that the construction furthermore is designed to facilitate assembly and production since the entire frame can, if desired, be fabricated from standard steel plate or rolled sheet metal sections. Machining operations have been reduced to a minimum so that an extremely satisfactory truck frame assembly has been designed to meet all the requirements of manufacture and service.

It will be understood that certain features of the passenger truck frame construction described herein relate to a preferred embodiment and that certain modifications may be made without departing from the scope of the invention. For example, some of the smaller parts such as the spring pads, may be castings. Also, the shape of several of the tubular members may be square, circular, or rectangular as desired and therefore it is not intended to be limited beyond the scope of the hereinafter appended claims.

We claim:

1. A railway truck frame having a pair of hollow side rails, a pair of hollow transoms extending laterally across the frame and between the rails near the central section thereof, said transoms comprising oppositely facing channel members, a pair of transition members forming the termini of each transom, and a reinforcing plate welded internally of each transition member, said plates being oblique with respect to the vertical center line of the transition members.

2. A railway truck frame having a pair of hollow side rails, a pair of hollow transoms extending laterally across the frame and between the rails near the central section thereof, said transoms comprising oppositely facing channel members, a pair of transition members forming the termini of each transom, the base of said structure being welded to the side rail and the opposite end of the structure being welded to the transom, a bulkhead in each side rail in registry with the structure base welds, a bolster anchor bracket welded to each side rail, and a bulkhead in each side rail welded in registry with the bolster anchor bracket.

3. A railway truck frame having a pair of hollow side rails, a pair of hollow transoms extending laterally across the frame and between the rails near the central section thereof, said transoms comprising oppositely facing channel members, a pair of transition members forming

the termini of each transom, the base of said structure being welded to the side rail and the opposite end of the structure being welded to the transom, a bulkhead in each side rail in registry with the structure base welds, a bolster anchor bracket welded to each side rail, a bulkhead in each side rail welded in registry with the bolster anchor bracket, and a plurality of sleeves in each side rail, said sleeves being welded to the inner face of one side rail member and to the edge of a registering aperture in the other side rail member.

4. In railway truck frame construction a transom member comprising a pair of oppositely facing channels welded longitudinally to form a box section, a transition structure including a hollow end portion extending from the bottom of the transom through the top of the transom and being welded to the bottom and top, the inner edge of the end portion sloping outwardly with respect to the transom to provide unaligned welds, a reinforcing collar welded circumferentially around the upper periphery of said end portion, and a bottom plate welded to the underside of said structure and the ends of said channels and having a slot therein in line with the hollow end portion of the said structure.

5. A transom construction in accordance with claim 4, in which the bottom plate is formed integrally with a section of a side rail member.

6. In railway truck frame construction a transom member comprising a pair of oppositely facing channels welded longitudinally to form a box section, a flattened collar extending from the bottom of the transom through the top of the transom and being welded to the bottom and top, the inner edge of the collar sloping outwardly with respect to the transom to provide unaligned welds, a reinforcing collar welded circumferentially around the upper periphery of said flattened collar, a bulkhead serving as an enclosure for the transom and welded thereto, and a bracket welded to one of said channels substantially midway between the termini thereof.

7. A unitary railway truck frame weldment comprising a pair of spaced hollow side rails fabricated of steel plate, at least one hollow transom extending laterally between the side rails near the central portion thereof and terminating short of the side rails, a hollow transition structure recessed into each end of the transom and welded thereto and to each side rail, and reinforcing means internally of said hollow transition structure.

8. A unitary railway truck frame weldment comprising a pair of spaced hollow side rails fabricated of steel plate, at least one hollow transom extending laterally between the side rails near the central portion thereof and terminating short of said side rails, and a transition structure welded at its outer end to each side rail and including an inner end portion recessed into the adjacent end of the transom and welded thereto, said inner end portion of each transition structure being hollow and extending the full height of the transom to provide an opening therethrough for the mounting of a swing link.

9. A unitary railway truck frame weldment comprising a pair of spaced hollow side rails fabricated of steel plate, at least one transom extending laterally between the side rails near the central portion thereof and terminating short of said side rails, a transition structure recessed into each end of the transom and welded thereto and to each side rail, and a bottom plate portion extending inwardly from each side rail and under-

lying and welded to said transition structure and the adjacent end of the transom.

10. A unitary railway truck frame weldment comprising a pair of spaced hollow side rails fabricated of steel plate, at least one hollow transom extending laterally between the side rails near the central portion thereof and terminating short of said side rails, a transition structure welded at its outer end to each side rail and including an inner end portion recessed into the adjacent end of the transom and welded thereto, said inner end portion of each transition structure being hollow and extending the full height of the transom to provide an opening therethrough for the mounting of a swing link, and a bottom plate portion extending inwardly from each side rail and underlying and welded to said transition structure and the adjacent end of the transom, said bottom plate portion having an opening therein underlying the hollow inner end portion of the transition structure.

11. In a unitary railway truck frame weldment having a pair of spaced hollow side rails connected by a plurality of transoms, the improved construction for at least one of said transoms that comprises a hollow box section member extending laterally between the side rails near the central portion thereof and terminating short of the side rails, and a transition structure extending between the opposite ends of said one transom and the adjacent side rail, said transition structure including an outer portion comprising laterally divergent side walls having their outer edges welded to the inner walls of the side rails and an inner end portion recessed into the adjacent end of said one transom and welded thereto.

12. In a unitary railway truck frame weldment having a pair of spaced hollow side rails connected by a plurality of transoms, the improved construction for at least one of said transoms that comprises a hollow box section member extending laterally between the side rails near the central portion thereof and terminating short of the side rails, and a transition structure extending between the opposite ends of said one transom and the adjacent side rail, said transition structure including an outer portion comprising laterally divergent side walls having their outer edges welded to the inner walls of the side rails and an inner end portion recessed into the adjacent end of the transom to provide an opening therethrough for the mounting of a swing link.

13. In a unitary railway truck frame weldment having a pair of spaced hollow side rails connected by a plurality of transoms, the improved construction for at least one of said transoms that comprises a hollow box section member extending laterally between the side rails near the central portion thereof and terminating short of the side rails, a transition structure extending between the opposite ends of said one transom and the adjacent side rail, said transition structure including an outer portion comprising laterally divergent side walls having their outer edges welded to the inner walls of the side rails and an inner end portion recessed into the adjacent end of said one transom and welded thereto, and a bottom plate portion extending inwardly from each side rail and underlying and welded to said transition structure and the adjacent end of the transom.

14. In a unitary railway truck frame weldment having a pair of spaced hollow side rails connect-

ed by a plurality of transoms, the improved construction for at least one of said transoms that comprises a hollow box section member extending laterally between the side rails near the central portion thereof and terminating short of the side rails, a transition structure extending between the opposite ends of said one transom and the adjacent side rail, said transition structure including an outer portion comprising laterally divergent side walls having their outer edges welded to the inner walls of the side rails and an inner end portion recessed into the adjacent end of said one transom and welded thereto, said inner end portion of each transition structure being hollow and extending the full height of the transom to provide an opening therethrough for the mounting of a swing link, and a bottom plate portion having an opening therein underlying the hollow inner end portion of the transition structure.

15. A construction in accordance with claim 8, in which the transition structure inner end has a swing link pin trunnion welded to its upper edge for suspension of a swing link through the structure inner end and the transom.

16. A unitary railway truck frame weldment comprising a pair of spaced hollow side rails fabricated of steel plate, at least one transom extending laterally between the side rails near the central portion thereof and terminating short of said side rails, a transition structure recessed into each end of the transom and welded thereto and to each side rail, a bottom plate portion extending inwardly from each side rail and underlying and welded to said transition structure at the adjacent end of the transom, said bottom plate portion of each side rail sloping inwardly and supporting the transom below the level of the side rails.

17. A unitary railway truck frame weldment comprising a pair of spaced hollow side rails fabricated of steel plate, at least one transom extending laterally between the side rails near the central portion thereof and terminating short of said side rails, a transition structure recessed into each end of the transom and welded thereto and to each side rail, a bottom plate portion extending inwardly from each side rail and underlying and welded to said transition structure and the adjacent end of the transom, the ends of the transom being beveled inwardly and the bottom plate portion of each side rail sloping correspondingly inward and supporting the transom below the level of the side rails.

18. A construction as claimed in claim 11, wherein the transition structure includes a top plate which overlies and is welded to the upper edges of the side walls thereof and extends outwardly into the top of the adjacent side rail and is welded thereto.

19. A unitary railway truck frame weldment comprising a pair of spaced hollow side rails fabricated of steel plate, at least one hollow transom extending laterally between the side rails near the central portion thereof and terminating short of said side rails, a transition structure welded at its outer end to each side rail and including an inner end portion welded to the adjacent end of the transom, said inner end portion of each transition structure being hollow and extending the full height of the transom to provide an opening therethrough for the mounting of a swing link, and a bottom plate portion extending inwardly

from each side rail and underlying and welded to said transition structure and the adjacent end of the transom, said bottom plate portion having an opening therein underlying the hollow inner end portion of the transition structure.

20. In a unitary railway truck frame weldment having a pair of spaced hollow side rails connected by a plurality of transoms, the improved construction for at least one of said transoms that comprises a hollow box section member extending laterally between the side rails near the central portion thereof and terminating short of the side rails, and a transition structure extending between the opposite ends of said one transom and the adjacent side rails, said transition structure including an outer portion comprising laterally divergent side walls having their outer edges welded to the inner walls of the side rails and an inner end portion welded to the adjacent end of said one transom.

21. In a unitary railway truck frame weldment having a pair of spaced hollow side rails connected by a plurality of transoms, the improved construction for at least one of said transoms that comprises a hollow box section member extending laterally between the side rails near the central portion thereof and terminating short of the side rails, and a transition structure extending between the opposite ends of said one transom and the adjacent side rail, said transition structure including an outer portion comprising laterally divergent side walls having their outer edges welded to the inner walls of the side rails and an inner end portion welded to the adjacent end of said one transom, said inner end portion of each transition structure being hollow and extending the full height of the transom to provide an opening therethrough for the mounting of a swing link.

22. In a unitary railway truck frame weldment having a pair of spaced hollow side rails connected by a plurality of transoms, the improved construction for at least one of said transoms that comprises a hollow box section member extending laterally between the side rails near the central portion thereof and terminating short of the side rails, a transition structure extending between the opposite ends of said one transom

and the adjacent side rail, said transition structure including an outer portion comprising laterally divergent side walls having their outer edges welded to the inner walls of the side rails and an inner end portion welded to the adjacent end of said one transom, said inner end portion of each transition structure being hollow and extending the full height of the transom to provide an opening therethrough for the mounting of a swing link, and a bottom plate portion extending inwardly from each side rail and underlying and welded to said transition structure and the adjacent end of the transom, said bottom plate portion having an opening therein underlying the hollow inner end portion of the transition structure.

23. In a railway car truck frame, a substantially hollow side rail member of plate elements welded together, a substantially hollow transom member of plate elements welded together, and a substantially hollow transition structure at the junction between said members, of considerably greater overall vertical dimension than the vertical dimension of one of said members at said junction, said structure also being substantially hollow, and of plate welded to said members.
